PARACHUTE PACK

Edward L. Hoffman, Dayton, Ohio

Application April 13, 1933, Serial No. 665,973

12 Claims. (Cl. 244—21)

(Granted under the act of March 3, 1883, as
amended April 30, 1928; 370 O. G. 757)

The invention described herein may be manufactured and used by or for the Government for governmental purposes, without the payment to me of any royalty thereon.

5 The present invention relates generally to improvements in parachute packs and more particularly to packs of the type adapted to be worn on the back of an aviator and the primary object of the present invention is to provide a non-rigid or soft pack which will readily conform to the body or seat of the wearer and yet retain its comparatively flat shape, even though worn upon the wearer's back in an upright position without the tendency to approach 10 a spherical or cylindrical form when in a packed condition.

A further object of the present invention is to provide in a pack of this character a stiffening frame so shaped and so positioned in the pack 20 that it is possible to maintain the folds of the parachute canopy in their normally folded position and the pack substantially flat even when worn in an upright position on the back or chest of the wearer and yet maintain the same 25 of such a flexible character that it is capable of readily conforming to the wearer's back or chest.

Further objects and advantages of my invention will be more fully set forth, reference being made to the following detailed description of 30 a preferred form of my invention and to the accompanying drawing in which:

Fig. 1 is a plan view of the pack as it is opened, illustrating the manner in which the stiffening frame is positioned therein;

35 Fig. 2 is a rear view of the container with a rip cord attached thereto;

Fig. 3 is an end view with a portion broken away illustrating the position of the stiffening frame when the parachute is packed within the 40 container;

Fig. 4 is a perspective view of the stiffening frame;

Fig. 5 is a view similar to Fig. 4 showing the 45 stiffening frame covered with flexible material; and

Fig. 6 is a part sectional view taken on the line 6—6 of Fig. 5.

Referring more particularly to the drawing wherein corresponding parts are designated by like numerals throughout the several views, the 50 parachute pack in one embodiment of my invention herein illustrated comprises generally a container, including a body portion 10, and a plurality of side portions 11 and 12, and an end flap 13, which is adapted to fold over the side

flaps and the body portion to retain a folded 5 parachute therein. This container is of a type set forth in my invention No. 1,774,513 issued September 2, 1930, wherein the end flap 13 is provided with an auxiliary flap 14, within which a pilot parachute is adapted to be folded, so that when the pack is released the pilot parachute will be forcibly thrown from the container into the air and readily withdraw the main chute 10 from the container.

In the above-referred-to patent, I make reference to the use of pockets herein designated by numerals 15 and 16, consisting of two pieces of webbing sewed at intervals onto the pack portion of the container at opposite sides thereof, leaving slack looped portions within which the suspension lines 17 of the main parachute are adapted to be tucked in the manner illustrated in Fig. 1.

The numeral 18 indicates a stiffening frame, 20 the outer dimensions of which are substantially equal to the dimensions of the body portion of the pack. As will be noted by referring to Fig. 5, this stiffening frame is covered with flexible material and is provided at its one end with a flap 19, to which is secured a plurality of fastening elements 20. These fastening elements are of the glove button type and as shown in Figs. 5 and 6 the female portion of the fasteners are secured on the flap 19 heretofore mentioned. 25 The male portion of the fasteners indicated by numeral 21 are carried on the body portion 10 on the pack adjacent the flap 13, as shown in Fig. 1. By providing releasable fasteners on the stiffening frame in the manner described, it will 30 be readily apparent that in emergencies the stiffening frame is readily removable from the pack. 35

Referring to Fig. 3, it will be noted that the canopy of the pack generally indicated by numeral 22 is folded back and forth on the body portion of the pack and that the stiffening frame is inserted between the folds of the canopy and so positioned as to lie substantially centrally of the pack when in a folded condition. By observing Figs. 4 and 5, it will be noted that the stiffening frame is substantially D-shaped, the central portion of which is cut-away so that when folded the material of the canopy will tightly pack within this hollow central portion. It will be further noted that the end opposite from the flap 19 is cut-away, as indicated by the numeral 23, within which the folds of the parachute are disposed. Consequently, when the pack is worn upon the back of a wearer, the folds of the parachute will be suspended over the end portion of 50 55

the frame and will be prevented from movement within the pack when the side flaps 11 and 12 and end flap 13 are connected together in packing.

- 5 While I have illustrated and described the preferred form of construction for carrying my invention into effect, it is to be understood that variations and modifications may be made without departing from the spirit of the invention.
- 10 I, therefore, do not wish to be limited to the precise details of construction set forth, but desire to avail myself of such variations and modifications as may come within the scope of the appended claims.
- 15 Having thus described my invention, what I claim as new and desire to secure by Letters Patent is:
- 20 1. In a parachute pack, a container for the parachute made of flexible material, including a body portion and a plurality of side flaps releasably connected to the edges of the body portion of said pack, a parachute folded in said container, and a stiffener frame longitudinally disposed within and approximately in the middle 25 of said pack to maintain said pack in a substantially flat condition.
- 25 2. In a parachute pack, a container for the parachute made of flexible material, including a body portion, and a plurality of side flaps releasably connected to the edges of the body portion of said pack, a parachute folded in said container and a stiffener frame, rectangular in shape, positioned in said pack between the folds of said parachute to maintain said pack substantially 30 flat and retain said parachute in folded condition.
- 30 3. In a parachute pack, a container for the parachute made of flexible material, including a body portion of rectangular shape, and a plurality of side flaps releasably connected to the edges of the body portion of said pack, a parachute folded in said container and a hollow frame of rectangular shape positioned in said pack between the folds of said parachute to maintain said pack substantially 35 flat.
- 35 4. A soft parachute pack comprising, a container for the parachute made of flexible material and including a body portion and a plurality of side flaps releasably connected to the edges of the body portion of said pack, a parachute folded in said container, and a readily removable hollow frame of rectangular shape adapted for being inserted between the folds of said parachute to maintain said pack substantially flat and prevent the folds of said 40 parachute from unfolding.
- 40 5. In a parachute pack, a container for the parachute made of flexible material, including a body portion of rectangular shape and a plurality of side flaps releasably connected to the edges of the body portion of said pack, a parachute folded in said container and a hollow stiffener frame having a shape conforming to the shape of the body portion of said pack inserted between the folds of said 45 parachute to maintain said pack substantially flat and prevent the parachute from unfolding, said frame having a covering of flexible material adapted for being removably secured to one end of the body portion of said container.
- 45 6. A soft parachute pack comprising, a container for the parachute made of flexible material and including a body portion and a plurality of side flaps releasably connected to the

edges of the body portion of said pack, a parachute folded in said container, a hollow stiffener frame having a shape conforming to the shape of the body portion of said pack inserted between the folds of said parachute to maintain said pack substantially flat and prevent the parachute from unfolding and a covering of flexible material for said frame, said covering having a flap provided at its one end and releasable fastening means for securing said flap to the body of said container. 10

5 7. A soft parachute pack comprising, a container for the parachute made of flexible material, including a body portion and a plurality of side flaps releasably connected to the edges of the body portion of said pack, a parachute folded in said container, and a hollow stiffener frame inserted between the folds of said parachute to maintain said pack substantially flat and prevent said 15 parachute from unfolding, the outer dimensions of said frame corresponding substantially to the dimensions of the body portion of said container.

10 8. A soft parachute pack comprising, a container for the parachute made of flexible material, including a body portion and a plurality of side flaps releasably connected to the edges of the body portion of said pack, a parachute folded in said container, and a stiffener frame inserted between the folds of said 15 parachute to maintain said pack substantially flat and prevent said 20 parachute from unfolding, the central portion of said frame being hollow to permit the folds of said 25 parachute to pack therein.

25 9. In a parachute pack adapted to be worn on the back of an aviator, a container for the 30 parachute made of flexible material, including a body portion and a plurality of side flaps releasably connected to the edges of the body of said pack, a 35 parachute folded in said container and a D-shaped frame adapted for being removably inserted between the folds of said 40 parachute to maintain said pack substantially flat and prevent said 45 parachute from unfolding, the one end of said frame being provided with a cut-away portion over which the folds of said 50 parachute are adapted to be draped to hold said folds in a suspended position when worn upon the back.

10 10. In a pack containing a parachute, a readily removable stiffener frame disposed within said pack adapted for maintaining said pack substantially flat when said 55 parachute is folded therein.

11. A stiffener frame for a 60 parachute pack adapted for being longitudinally disposed in said pack between the folds of the canopy of said 65 parachute, said frame including a covering of flexible material having a flap at its one end provided with releasable fasteners adapted for being detachably secured to said pack.

12. A stiffener frame for a 70 parachute pack worn upon the back of an aviator adapted for being longitudinally disposed in said pack between the folds of the canopy of said 75 parachute, said frame including a covering of flexible material having a flap at its one end adapted for detachable connection with said pack, the opposite end of said frame being provided with a cut-away portion over which the folds of said 80 parachute are adapted to be draped to hold said folds in a suspended position when on the back of the 85 wearer.

EDWARD L. HOFFMAN.
